CLAIM

The ornamental design for a modular electronic device, as shown and described.

DESCRIPTION

FIG. 1 is a top, front, right, perspective view of a modular electronic device.

FIG. 2 is a top, rear, right perspective view of the modular electronic device of FIG. 1.

FIG. 3 is a front view of the modular electronic device of FIG. 1.

FIG. 4 is a rear view of the modular electronic device of FIG. 1.

FIG. 5 is a top view of the modular electronic device of FIG. 1.

FIG. 6 is a bottom view of the modular electronic device of FIG. 1.

FIG. 7 is a right side view of the modular electronic device of FIG. 1; and,

FIG. 8 is a left side view of the modular electronic device of FIG. 1.

The broken lines in the drawings are for the purpose of illustrating portions of the modular electronic device that form no part of the claimed design.

1 Claim, 4 Drawing Sheets
